RAILWAY CAR FLUSH DOOR STRUCTURE

Thomas C. Soddy, Downers Grove, Ill., assignor to Chicago Railway Equipment Company, Chicago, Ill., a corporation of Illinois

Filed Apr. 24, 1958, Ser. No. 730,624

15 Claims. (Cl. 20—23)

This invention relates to railway car doors, such as refrigerator car doors, and more particularly to supporting, operating and holding means for sliding car doors of the type which close into a door opening in a side wall of a car, the door when fully closed being substantially flush with the side wall.

When a railway car equipped with a sliding door of the class described is subjected to endwise impacts, such as occur in switching operations, if the door should be open (and not latched in fully open position), it will slide endwise repeatedly with considerable momentum. With prior supporting and operating means, this has resulted in the front or rear end of the door bouncing against the front or rear stops for the door, depending upon the direction of impact, resulting in such dynamic shocks that the door stops may be knocked off the car or the door may be badly damaged, or the track or guide damaged. One of the objects of this invention is the provision of improved door supporting and operating means which acts automatically, upon sliding of the door in closing direction, to swing both the front and rear ends of the door into the door opening. Thus, should the door be open when the car is subjected to an impact which makes the door slide in closing direction, the door will automatically move into such a position within the door opening that subsequent end impacts cannot cause it to move.

A sliding door of the class described when closed may be subjected to relatively high internal loads tending to push it outwardly. For example, in a car loaded with barrels of merchandise, barrels may break loose and wedge against the inside surface of the door. Another object of the invention is the provision of means for locking the door in closed position to resist such internal loads.

In prior sliding door constructions, the weight of the door when closed is borne by the door supporting and operating means, and vibration of the car while in service is apt to cause wear of parts and sagging of the door. A further objection of this invention is the provision of means for automatically taking the load due to the weight of the door off the supporting and operating means whenever the door is closed to avoid such wear and sagging.

Sliding doors of the class described usually are supported by a lower track and retained at the top by a top retainer or guide. When a car is subjected to severe endwise impact, the stress is such that the portion of the car side plate above the door opening tends to buckle upward and the portion of the car side sill below the door opening tends to buckle downward, with resultant tendency to spread apart the track and top retainer. With prior constructions, this spreading could result in the disengagement of the door supporting and operating means from the top retainer. A further object of this invention is the provision of safety means as a part of the door supporting and operating mechanism which acts to prevent such disengagement. Other objects and features will be in part apparent and in part pointed out herein-after.

2

In the accompanying drawings, in which several of various possible embodiments of the invention are illustrated,

Fig. 1 is a view in elevation of a side wall of a refrigerator car equipped with a door structure of this invention, the door being shown in closed position;

Fig. 1A is an enlarged vertical section taken on line 1A—1A of Fig. 1;

Figs. 2 and 3 are enlarged vertical sections taken on lines 2—2 and 3—3, respectively, of Fig. 1, the middle portion of the door being broken away in each instance;

Fig. 4 is a vertical section taken on line 4—4 of Fig. 2;

Fig. 5 is an enlarged horizontal section taken on line 5—5 of Fig. 1;

Figs. 6—9 are views similar to Fig. 5 but illustrating various moved positions of the door;

Fig. 10 is a view in elevation of a side wall of an insulated box car equipped with a door structure of this invention, the door being shown in closed position;

Fig. 11 is an enlarged vertical section taken on line 11—11 of Fig. 10, the middle portion of the door being broken away;

Fig. 12 is an enlarged horizontal section taken on line 12—12 of Fig. 10; and,

Fig. 13 is a view similar to Fig. 12 and showing a moved position of the door.

Corresponding reference characters indicate corresponding parts throughout the several views of the drawings.

30 A railway refrigerator car side wall 1 has a door opening 3. A relatively thick sliding door 5 is adapted to occupy a closed position in the opening 3 substantially flush with the side wall 1. At the bottom of door opening 3 is a threshold plate 7 (see Figs. 1A, 2 and 3) which is inclined upward from outside to inside. This plate lies outside a bottom stop 9. At the top of the door opening is a header 11. At the left and right ends of the door opening there are door posts 13 and 15.

40 The door 5 comprises a rectangular wood frame 17, a sheet metal outside panel 19 and a plywood inside panel 21. Frame 17 is made so that the door 5 has a rabbet 23 all around its edge on the inside. Rubber sealing strips such as indicated at 25 are provided around the frame on the inwardly facing surface of the rabbet 23 for sealing engagement with stop 9, header 11 and posts 13 and 15 when the door is closed. The thickness of the door, as shown, is the same as the thickness of the car wall and, when the door is closed, with the rubber sealing strips compressed, its outside face is flush with the outside of the car wall and its inside face is flush with the inside of the car wall. The door has a hand hold 27 at its right end. Rivets 29 are provided in side wall 1 adjacent the right end of the door opening for a special purpose to be described.

50 Door 5 is part of a door assembly A including front and rear rotary mounting shafts 31F and 31R extending vertically on the outside of the door and journaled in upper, lower and intermediate bearings 37. Shaft 31F is located near the front end 39 of the door, and shaft 31R is located near the rear end 41 of the door. The "front" end of the door is its end which leads and the "rear" end of the door is its end which trails as the door slides in closing direction, which is toward the left as viewed in Figs. 1 and 5—9. Fixed on the upper and lower ends of each of shafts 31F and 31R are crank arms 43 and 45. Extending longitudinally on the outside of the car side wall below the door opening is a track 47. Extending longitudinally on the outside of the car side wall above the door opening is a top retainer or guide 49 of inverted J-section providing a downwardly opening channel 50. Each of the lower crank arms 45 has a

roller carriage 51 vertically pin-connected at its free end as indicated at 53, whereby the crank arms may swing horizontally on the vertical axes of the pin-connections. Each carriage 51 carries rollers 55 riding on track 47 and has hook portions such as indicated at 57 which extend under the track. Each of the upper crank arms 43 has a roller 59 on a vertical pin at its free end, the roller riding in the channel portion 50 of the guide 49. When the door is in closed position (Figs. 1 and 5) upper and lower crank arms 43 and 45 of both mounting shafts 31F and 31R extend from the shafts longitudinally of the car in the direction of opening movement of the door, which is toward the right as viewed in Figs. 1 and 5. To open the door, it is necessary to swing it out of the door opening 3, the crank arms 43 and 45 swinging from the stated longitudinal position (Fig. 5) to an outwardly extending lateral position (Fig. 9). Then the door may be moved longitudinally on the outside of the car to a retracted position clear of the door opening by rolling the entire door assembly to the right on the track 47.

Door assembly A further comprises front and rear rotary locking shafts 61F and 61R extending vertically on the outside of the door each journaled in upper, lower and intermediate bearings 62. The front locking shaft 61F is located inward of and closely adjacent the front mounting shaft 31F. The rear locking shaft 61R is located inward of and closely adjacent the rear mounting shaft 31R. The locking shafts are rotatable independently of the mounting shafts. Each locking shaft has an eccentric lug 63 at each end. For each locking shaft, there is a pair of keepers 65 on the car side wall, one above and the other below the door opening. Each keeper 65 has an angled slot 67 (see Fig. 5) for receiving the respective lug 63 whereby upon rotation of a respective locking shaft in one direction (counterclockwise for shaft 61F and clockwise for shaft 61R as viewed from above), the lugs thereon are cammed inward and the door is forced closed and locked, and on rotation of the shaft in the opposite direction, the lugs thereon are cammed outward and the door is unlocked and forced in the direction out of the door opening. Each locking shaft has a handle 69 pivoted at 70 thereon. When the door is closed and locked, these handles occupy a position generally flat against the outside of the door inclined downward from their pivotal connections 70, with one handle crossing on the outside of the other and held in a catch 71 on the outside of the door. The handles are held against play by their lugs 69a and 69b. The handles are adapted to be swung up to horizontal position and then swung out for rotating the locking shafts to unlock the door and force it in the direction out of the opening, the left handle being swung clockwise and the right handle counterclockwise as viewed from above for this purpose.

For each of the mounting shafts 31F and 31R there is a stop 73 for restricting the rotation of the shaft in door-opening direction to approximately 90°, and thereby limiting the rotation of the crank arms to 90°. As shown in Figs. 1 and 4, the stop 73 for each mounting shaft comprises an arm having an arcuate end portion 75 welded on the shaft immediately below the upper bearing for the shaft. The arm extends tangentially from the shaft and has an angled end portion 77 engageable flatwise with the outside of the door when the shaft is rotated from its door-closed to its door-open position. Fig. 4 shows the front shaft 31F and the stop or arm 73 thereon in the door-open position in dotted lines, and in the door-closed position in solid lines.

Bumpers 79 are provided on the side wall 1 to limit sliding of the door in opening direction. Latch means 81 of any suitable construction, details of which are not essential, is provided on the side wall 1 for latching the door in fully open position.

Means is provided whereby, as the door 5 in sliding in closing direction (toward the left as viewed in Figs.

1 and 5-9) nears the end of its closing movement, the door is automatically swung into substantially closed position in the door opening 3. This feature is particularly desirable in conjunction with the latch means 81 to avoid 5 banging back and forth of the door in case it should be left partially opened and the car subsequently subjected to impacts such as occur in switching operations. As 10 shown, this means comprises a so-called front kicker stop 83 on the outside of the car side wall below door opening 3 adjacent the front end of the door opening. This 15 stop 83, as shown, consists simply of a lug welded on the side wall of the car projecting outward from the car in position for engagement of its rear edge by the front roller carriage 51 when the latter reaches a position spaced from the front end of the door opening a distance corresponding to the throw of the crank arms 43 and 45 plus the distance from the front end of the door to the front mounting shaft 31F. Accordingly, when the 20 door assembly slides in closing direction, the door moves parallel to the car side wall until the front roller carriage strikes the stop or lug 83 (see Fig. 9), whereupon momentum causes the front edge of the door to swing inward. A stop 85 may also be provided in the top guide 49 engageable by the roller 59 of the upper front crank arm 25 43 to arrest this roller when the front roller carriage strikes stop 83.

The automatic swinging means further comprises a so-called closing kicker 87 on the outside of the car side wall below the door opening adjacent the rear end of the 30 door opening. This kicker, as shown, consists of a lug welded on the side wall of the car and projecting outward therefrom in position for engagement by an eccentric projection 89 on the rear lower crank arm 45 upon engagement of the front roller carriage 51 with stop 83. 35 As the door assembly is sliding toward closed position, projection 89 engages kicker 87 (see Fig. 9), causing the rear lower crank arm to swing clockwise as viewed from above to carry the rear edge of the door into the door opening. This brings rear crank arm 45 under stop 40 83 and at the same time forward crank arm 45 moves under the adjacent keeper 65. Thereafter, rough track, buffing impacts or other forces would not be able to move the door upwardly because of the engagement of the arms with the overlying elements.

45 The bottom edge of the door is provided adjacent each end thereof with a ball roller 91 (see Figs. 1 and 1A) adapted to ride up the inclined portion of the threshold and lift the door up slightly to take the weight of the door off the roller carriages. This takes the load off the 50 rollers 55 when the door is closed, thereby avoiding wear and sagging of the door such as may otherwise occur due to vibration of the car while in service.

Extending upwardly from upper crank arms 43 are C 55 shaped retainers 93 (Figs. 1-3) having upper portions 95 overlying guide 49 and prevent rollers 59 from dropping below and moving out from behind guide 49 because of vertical buckling of the guide. Retainer 93 will also prevent dropping the door in the event of loss or displacement of track 47. These retainers are similar 60 to those shown in my copending application entitled House Car Side Door Structure, Serial No. 718,865, filed March 3, 1958.

There is a rain guard 97 on the car side wall 1 which 65 extends outward from the wall above the door opening 3 and which has gaps as indicated at 98 for accommodating the upper keepers 65 and the upper ends of shafts 31F and 31R and shafts 61F and 61R. A stop 99 constituted by a flange on the rain guard is provided for engagement by the rear mounting shaft 31R to keep the door 70 from moving to the right during the initial phase of opening of the door.

Operation is as follows:

To open door 5, front (left) locking shaft 61F is 75 manually rotated clockwise as viewed from above by

means of its handle 69 enough to relieve the pressure on sealing strip 25 at the front end of the door against front door post 13 (see Fig. 6). Only a relatively small degree of rotation of shaft 61F is required for this purpose. Then rear (right) locking shaft 61R is manually rotated counterclockwise by means of its handle 69 to a position such as shown in Fig. 7. This brings the rear (right) end of the door partly out of the door opening. It also automatically brings the front (left) end of the door partly out of the door opening (see Fig. 7) by reason of the door pivoting about the line of contact of the rear end of the door and rear door post 15, this line being indicated at X in Fig. 7. The outward movement of the left end of the door thrusts lugs 63 on shaft 61F against the outer sides of slots 67 and thus rotates the shaft to the position shown in Fig. 7. During the operation of rear locking shaft 61R, stop 99 (Figs. 1, 3) keeps the door from moving to the right to any considerable extent until the upper end of shaft 61R slides out past stop 99, thus preventing lugs 63 on shaft 61R from moving too far to the right in their keeper slots 67, which would make it difficult to pull the door out. Then the rear end of the door is pulled completely out of the opening by grasping handle 27, and the door is moved rearward (toward the right). As the door is moved rearward, its inside face wipes over rivets 29 (see Fig. 8), and this swings the front (left) end of the door completely out of the door opening. Then the door may be manually rolled rearward to completely open position clear of door opening 3 and latched in this position by the latch means 81 (Fig. 1).

To close the door, the latch means is released, and the door rolled forward. Forward linear movement of the door is arrested when the front roller carriage 51 strikes the front kicker stop 83 (see Fig. 9) and the roller 59 on the upper front crank arm 43 strikes the stop 85 (Fig. 1). The front end of the door swings into the door opening 3 and the rear end of the door is kicked into the door opening by the engagement of the projection 89 on the rear lower crank arm 45 with the kicker 87, the door ending up in a position approximately as shown in Fig. 7. As the door swings into the door opening, the eccentric locking lugs 63 enter the slots 67 in the keepers 65. Then, the rear (right) locking shaft 61R is given a full swing in locking direction. This automatically moves the front (left) end of the door into the Fig. 6 position, the door pivoting on front gasket 25, and rotates the front (left) locking shaft 61F to the Fig. 6 position. Finally the front locking shaft 61F is manually rotated through the remainder of its swing to complete the closing of the door and compress the sealing strips.

If the door should be left partially open, upon an impact which causes the door to slide in opening direction (toward the right), the door will be automatically latched in fully open position by the latch means 81. Upon an impact which causes the door to slide in closing direction (toward the left), the door will automatically swing into the Fig. 7 position, and remain there. Thus, banging back and forth of the door such as would otherwise occur if the door should be left partially open is avoided.

Figs. 10-13 show the invention as applied to an insulated box car side wall 101 having a door opening 103. The construction is generally the same as that shown for the refrigerator car, except that the wall 101 is thinner than the wall 1, and the box car door, which is designated 105, is thinner than the refrigerator car door. Also, a different safety means, constituting a feature of this invention, is used for preventing rollers 59 from coming out of guide 49. Aside from the difference in the door thickness, the door assembly shown in Figs. 10-13 is the same as that shown for the refrigerator car door, and the parts shown in Figs. 10-13 which corre-

spond to those shown in Figs. 1-9 bear the same reference characters as in Figs. 1-9.

The door structure for the insulated box car is shown herein in addition to the door structure of the refrigerator car door because there is a difference in the mode of operation due to the insulated box car door 105 being relatively thin. Being thin, door 105 would not pivot properly along a line such as X (Fig. 8) as does the refrigerator door to bring the front end partly out of the door opening as shown in Fig. 7 for the refrigerator car door. However, because the door 105 is thin, once its left locking shaft 61F has been rotated a small amount and its right locking shaft 61R has been rotated the appropriate amount, even though the front end of the door 105 does not come out to a position corresponding to that shown in Fig. 7, it is relatively easy manually to pull the door out by the right locking shaft without any further operation of the left locking shaft.

The door is held in opened position by a latch 111 pivoted on a mounting bracket 113 secured to the side wall. The latch is held horizontal, as shown, when the door is closed but rides up over a hook 117 on the rear carriage 119 when the door is opened.

Also, the operation on closing the relatively thin insulated box car door 105 is slightly different from that for the refrigerator car door in that before the box car door is manually moved to close it, the left (front) locking shaft 61F needs to be rotated to the left to position its lugs 63 for entry into the respective keeper slots 67. Otherwise, the operation on closing is the same as that for the refrigerator car door.

The safety means for the insulated box car door comprises a safety guard angle bar 107 in the guide 49 over the door opening and a similar bar 109 in extension of bar 107 beyond the door opening. These angle bars 107 and 109 are secured on the rain guard 97, and have one leg extending upward for engagement by the bottoms of the upper crank arms 43 to keep the rollers 59 in the channel portion 50 of the guide 49.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

I claim:

1. Supporting and operating means for a sliding rail-way car door of the type which closes into a door opening in a side wall of the car substantially flush with said side wall, comprising a track on the outside of said side wall below the door opening, a pair of upright mounting shafts spaced apart lengthwise of the door and journaled on the door to rotate freely during door shifting movements but held against vertical movement on the door, crank arms fixed on the lower ends of the mounting shafts, spaced carriages riding on the track alongside said opening and beyond the same, the outer end of each crank arm having a pivot support on a respective one of said carriages, said crank arms being swingable readily on their pivot supports to move the door in and out of the door opening, directly transversely of the general plane of the car side wall, a pair of vertical locking shafts, one adjacent each mounting shaft, rotatably mounted on and carried by the door and rotatable independently of said mounting shafts, eccentric lugs on the lower ends of the locking shafts, keepers fixed on the side wall for receiving said lugs, said lugs being rotatable by said locking shafts independently of the mounting shafts into positions behind said keepers to positively resist movement of the door outwardly of the door opening, and means automatically swinging both crank arms on the carriages independently of the locking shafts to move the door into closed position in the door opening.

as the door is moved from an open position to a position abreast of the door opening.

2. Supporting and operating means as set forth in claim 1 wherein said swinging means comprises a stop on the side wall engageable by the front carriage to arrest the latter in a position wherein it is spaced from the front end of the door opening a distance corresponding to the sum of the distance from the front end of the door to the front mounting shaft and the throw of the crank arms, and a kicker on the side wall engageable by the lower rear crank arm to swing this crank arm and the rear end of the door inward.

3. Supporting and operating means as set forth in claim 1 wherein each of the mounting shafts has an arm thereon engageable with the outside of the door when the shaft rotates in door-opening direction to limit the rotation of the shaft and the swing of the door.

4. Supporting and operating means as set forth in claim 3 wherein said arm consists of a bar secured to the outside of the mounting shaft extending tangentially from the mounting shaft and having an angled end portion engageable flatwise with the outside of the door.

5. Supporting and operating means as set forth in claim 1 wherein the locking shafts have handles pivotally connected thereto, said handles being adapted to occupy a position crossing each other and generally flat against the outside of the car door when the door is positioned fully within the door opening, and an upwardly opening catch on the door receiving the outer of said crossed handles in said position whereby the outer handle holds both locking shafts against rotation.

6. Supporting and operating means as set forth in claim 1 wherein the side wall at the door opening has a threshold inclined upward from outside to inside and wherein the door has rollers at the bottom which ride up the threshold to lift the door as it moves into the door opening and relieve the crank arms, carriages and track of the weight of the door.

7. Supporting and operating means for a sliding railway car door of the type which closes into a door opening in a side wall of the car substantially flush with said side wall, comprising a track on the outside of said side wall below the door opening, a guide on the outside of the side wall above the door opening, front upper and lower crank arms and rear upper and lower crank arms on the door, carriages pivoted on the ends of the lower crank arms riding on the track, means on the ends of the upper crank arms guided by the guide, said crank arms being swingable in and out for movement of the door into and out of closed position, said door when swung out of closed position being movable longitudinally along the side of the car in rearward direction to a retracted position clear of the opening and being movable back in forward direction for closing thereof, a stop on the side wall engageable by the front carriage to arrest the latter in a position spaced from the front end of the door opening a distance such as to enable swinging of the front end of the door into closed position in the door opening, and a kicker on the side wall engageable by the lower rear crank arm to swing this arm and the rear end of the door inward.

8. In a railway car side wall and flush sliding door structure, upright mounting shafts freely journaled on the door near its front and rear ends, each mounting shaft having a lateral arm at the bottom of the door with a vertical trunnion at its outer end, a track spaced outwardly from and mounted on the side wall, spaced carriages near the front and rear of the door respectively and movable over said track and individually freely journaling said trunnions, an upright operating shaft journaled on the door near the rear end of the door and provided with an operating handle and with an offset locking lug, a cam-like keeper on the side wall engaging said lug, rotation of said handle in opposite directions thrusting the lug against the keeper to move the rear

portion of the door transversely of the side wall inwardly and outwardly of the door opening, an outwardly projecting element on the side wall near the rear end of the door opening and engaging the inner face of the door as the door moves past the element to automatically swing the forward portion of the door outwardly and to swing said mounting shafts about their journals and pivots.

9. A railway car sliding door with supporting and operating means of the type which moves the door transversely of the car wall into a door opening where the door is flush with the wall, comprising a track on the wall, carriages movable along said track, door support arms spaced apart lengthwise of the door each having a vertical trunnion at one end freely journaled on a respective carriage and a vertical journal at the other end freely pivoted on the door, an upright operating shaft journaled on the door near one end and having a crank arm provided with a locking lug, a keeper secured to the wall and provided with cam faces cooperating with said lug to force the adjacent end of the door inwardly of said opening when the shaft is rotated in one direction, and to force the door outwardly of said opening when the shaft is rotated in the opposite direction, opposing elements on the edge of the door near said operating shaft and on the wall, said elements contacting upon initial rotation of the operating shaft in the last mentioned direction to form a pivot for the door about said edge and to swing said crank arms on the door and on said carriages to clear the door from the door opening as the shaft rotation is continued.

10. A railway door with supporting and operating means according to claim 9 in which the upright operating shaft is provided with a handle lever by which it is rotated, and the crank arms are provided with stops limiting their rotation on the door, whereby the movement of said handle to rotate the cooperating shafts in the second mentioned direction is terminated when the handle extends approximately normal to the door.

11. Supporting and operating means for a sliding railway car door according to claim 1 in which at least one of the crank arms moves immediately beneath one of the keepers on the side wall when said crank arm swings into door closing position so that the keeper holds the crank arm and door against upward movement relative to the side wall.

12. Supporting and operating means for a sliding railway car door according to claim 1 in which a stop is fixed on the side wall and projects outwardly therefrom, and a lug on one of the carriages engages with said stop to arrest movement of the carriage toward door closing position and thereby swings the crank arm toward the car side wall and beneath said stop whereby said track, stop and carriage hold the door against vertical movement relative to the car side wall when in closed position.

13. In combination in a railway car side wall with a door opening, there being upright front and rear posts at opposite ends thereof, and a door fitting into said opening substantially flush with the wall, a track mounted on the wall abreast of and beyond said opening, carriages on and movable along the track, horizontal arms spaced apart lengthwise of the door, each freely journaled at one end on said door and at the other end on one of said carriages and supporting the door, an upright shaft journaled on the door near the end thereof adjacent to said rear post, offset locking lugs at the ends of said shaft, keepers on the wall with cam faces, a manually operable lever handle on said shaft and movable in a direction toward said front post and toward the door to rotate the shaft in one direction to thrust said lugs against keeper cam faces and move the adjacent end of the door inwardly of said opening, said lever handle being movable away from the door and then away from said front post, first to thrust said lugs against keeper cam faces and

move the adjacent end of the door outwardly of said opening and then to move the rear end of the door against said rear post and thereby to swing the front end of the door about said rear post as a pivot and out of the opening, said horizontal arms swinging upon their pivots on said carriages under the thrust of the moving door, and then to move the door along said wall past said rear post.

14. Supporting and operating means as set forth in claim 1 in which there is an elongated guide fixed on the outside of the side wall above the door opening and forming a downwardly open channel, keepers fixed on the side wall above the door opening and below said guide, eccentric lugs on the upper ends of the locking shafts and rotatable by the latter into engagement with said keepers above the door opening, crank arms on the upper ends of the mounting shafts above the level of and movable over said eccentric lugs on the upper ends of the locking shafts and the keepers therefor, said latter-mentioned crank arms having elements at their swinging ends received in and retained by said channel in said guide.

15. In combination, a railway car wall having a door opening and a track alongside and below said opening and a downwardly opening channel-section guide above and alongside said opening, carriages with grooved wheels

10

5 on said track, and a door having a vertical mounting shaft with crank arms at its lower end, the lower crank arm being pivoted at its outer end on said carriage, a crank arm at the upper end of said mounting shaft with its terminal received in said guide and limiting movement of the door outwardly from the car side, keepers on said wall above and below said opening, and a locking shaft journaled on said door adjacent to said mounting shaft with offset locking lugs at top and bottom, movable by rotation of the locking shaft into engagement with said keepers, said mounting shaft upper crank arm being movable over said locking shaft top lug and the keeper therefor.
